UNITED STATES PATENT OFFICE.

ARTHUR B. GRIFFEN, OF VERONA, NEW JERSEY.

SMELTING OR MELTING FURNACE.

No. 800,148.

Specification of Letters Patent.

Patented Sept. 26, 1905.

Application filed April 13, 1904. Serial No. 203,001.

To all whom it may concern:

Be it known that I, ARTHUR B. GRIFFEN, a citizen of the United States of America, residing at Verona, in the county of Essex and State 5 of New Jersey, have invented certain new and useful Improvements in Smelting or Melting Furnaces, of which the following is a specification.

My invention has reference in general to 10 melting or smelting furnaces of that class in which the molten charge is removed by tilting the furnace, and in particular it relates to reverberatory furnaces in which the charge is melted by the use of liquid, gaseous, or equivalent fuel in connection with a suitable burner or burners.

My invention has for its objects, first, to 15 reduce to the greatest possible extent the volatilization or distillation of the volatile constituents of alloys—such, for instance, as brass—when being melted in the furnace for the purposes of casting or running off; secondly, to improve and simplify the general construction and operation of furnaces having 20 two heating-chambers.

To these ends my invention consists in the 25 features of construction hereinafter described, and shown in the accompanying drawings and specified in the claims at the end of this 30 description.

Figure 1 represents a side elevation of a 35 furnace embodying my invention. Fig. 2 is a vertical longitudinal section thereof on the line 2 2, Fig. 4. Fig. 3 is a transverse section on the line 3 3, Fig. 1. Fig. 4 is an end elevation. Fig. 5 is a section on the line 5 5, Fig. 2, showing the furnace partially tilted into a position for taking up the ladle. Fig. 6 is a similar view showing the furnace in a 40 pouring position. Fig. 7 is a detail view showing a special construction for the ladle and its carrying-arms.

Similar letters and numerals of reference 45 designate corresponding parts throughout the several views of the drawings.

Referring now to the drawings, the letter A designates the body of the furnace, which is preferably made in cylindrical form and consists, as usual, of a metallic shell 1, having 50 a suitable refractory lining 2—for instance, fire-brick—and its heads 3 and 4 provided with usual hollow trunnions 5 and 6, for which suitable bearings are provided in the end frames B.

55 In the present example I have shown the trunnions 5 and 6 grooved peripherally and

resting on supporting-rollers 7, mounted in the end frames, so as to render the operation of oscillating or tilting the furnace-body as easy as possible. For tilting or oscillating 60 the furnace I make use of a worm 8, having bearings in the end frames B and provided with a suitable operating handle or wheel C. This worm engages with a worm-wheel 9, mounted on a shaft 10, having at its opposite 65 end a gear-wheel 11, engaging with a circular rack or gear 12, formed on the front head 3. Of course it is to be understood that any other suitable means for oscillating or tilting the furnace-body can be substituted for that 70 shown, the particular means employed forming no part of my present invention.

In the forms of tilting melting-furnaces heretofore used the charge took up the entire 75 hearth formed by the lower portion of the cylinder or other furnace-body and a heating-flame was introduced at opposite ends of the cylinder, or in some cases only at one end, the whole forming substantially a reverberatory furnace in which the charge was brought 80 into a molten condition and was discharged directly from the hearth by tilting or oscillating the furnace-body or by tapping in a usual manner.

According to my invention, I form the cylindrical furnace-body with two distinct but 85 communicating chambers D and E, divided one from the other by a partition P, having an eccentric opening *a* therein for establishing communication for the passage of molten 90 metal from one chamber to the other when the furnace-body is oscillated or tilted in the proper direction. The two chambers are arranged in axial line, and the chamber E, I shall hereafter term the “preheating-chamber” 95 and the chamber D the “augmenting-chamber,” the latter being heated to a temperature exceeding that of the preheating-chamber by several hundred degrees.

The preheating-chamber E is provided with 100 a charging-opening *e* for the introduction of the material or metal to be heated, which said opening serves also as a discharge for the gases or flame and may or may not be placed in communication with a chimney, according 105 to circumstances. The augmenting-chamber is provided with a pouring-opening *d*, which during the melting of the charge is closed by a suitable cover *f*, of refractory material. The jet or flame, preferably that produced by 110 an oil-burner (shown by broken lines in Fig. 2) of well-known construction, is introduced

through the hollow journal 5 and passing through the augmenting-chamber D and the opening *a* in the partition P enters the pre-heating-chamber E, containing the charge, and 5 passes out through the charging-opening *c*. A second burner F' (also indicated by lines in Fig. 2) may be caused to enter the other trunnion 6, the two flames or jets then meeting in the preheating-chamber. The purpose 10 of this burner is to act as a supplemental heat-producing agent in case the heat derived from the burner F is found not to be sufficient to properly melt the charge. In the normal or melting position of the furnace-body A the 15 opening *a* in the partition P is near the top of the furnace or above the level of the charge and to the rear of its center line, as shown in Fig. 3, and the charge molten in the chamber E consequently remains in said chamber while 20 the furnace-body is in its normal position.

By turning the furnace-body in the direction of arrow 10, Fig. 3—that is, in a direction reverse to that in which it is turned for pouring—through an angle of approximately 25 ninety degrees the two chambers D and E are brought into communication at or near their bottoms through the partition-opening, and the molten material flows from the chamber E into the chamber D. Before the time of 30 transfer of the molten metal the flame at the burner or burners is shut off, and consequently contact of the molten metal with air-oxidizing flame is avoided.

In order to take up the entire charge from 35 the chamber E, the chamber D is made larger in diameter than the chamber E or its bottom is located at a lower level than that of chamber D. If the furnace-body is now turned in the direction for pouring—that is, in the direction of arrow 11, Fig. 3—the charge passes through the pouring-opening *d* into the ladle or mold, as the case may be, its escape from 40 one chamber into the other being prevented by the partition-wall P, Fig. 6.

45 It will readily be understood that when the molten metal, which is brought close but not quite to the pouring condition in the chamber E, enters the chamber D it meets with the highly-heated walls of the same and is quickly 50 raised to the proper temperature for casting. By this means I reduce volatilization of metals or such alloys as contain volatile constituents in the preheating-chamber, as I can employ temperatures somewhat below that necessary 55 for placing the material in a condition for pouring and then quickly raise the temperature to the proper degree without the charge being subjected to an oxidizing-flame, and so 60 reduce loss by volatilization in the augmenting-chamber.

In tilting of oscillating furnaces of the type generally employed it has heretofore been necessary to shift the position of the receiving-ladle G with the turning movement of the 65 furnace so as to follow the movement of the

pouring-opening with the ladle, and to approximately empty the furnace it was necessary to pass the handles of the ladle at right angles to the longitudinal axis of the furnace. To avoid this inconvenience and loss of time, I 70 attach to the shell of the furnace-body adjacent to the pouring-openings supports II II, provided with bearing *h* for the carrying-arms *g g'* of the ladle G, Figs. 5, 6, and 7. In order to clear the framework of the furnace, I preferably make the single carrying-arm *g* of the ladle sectional, Fig. 7, and detach the same when the ladle is hung on the furnace, so that the ladle can move with the furnace throughout its complete throw. Any 75 suitable means, such as the tongue-and-socket connection *i i'*, Fig. 7, may be used for readily connecting and disconnecting the two sections of one of the carrying-arms.

In tilting furnaces of the character herein 80 described considerable inconvenience has been caused by the burning away of the fire-brick or refractory lining at and surrounding the pouring and charging openings, as well as the burning away of the surrounding iron 85 shell in view of the locally-applied intense heat, thus necessitating the shutting down of the furnace for repairs. To enable ready repairs to be made, I make use of separate throat-pieces I and J for both the charging and pouring openings, Figs. 1, 2, and 3. These are 90 formed or built up of fire-clay or other refractory material and held in position by suitable metallic collars *j* and *j'*, bolted or otherwise secured to the shell 1. These throat-pieces can be readily replaced when burned or 95 worn out in a very short space of time.

While I have herein shown the furnace-body in cylindrical form, it is of course to be understood that it may be made in other forms 100 while retaining all the advantages pertaining to the cylindrical construction.

While in the present example I have shown the pouring-opening *d* arranged substantially in line with the charging-opening *c*, the pouring-opening may be located in the lead of the charging-opening for the purpose of pouring from the chamber D without disturbing the contents in the chamber E. This form is particularly intended for continuous-feed furnaces—that is to say, those in which only part 115 of the charge is conducted from chamber E to chamber D, while new material is fed through the charge-opening. To this same end the furnace could be radially tapped at the chamber D below the pouring-opening—that is, 120 near the bottom of the hearth.

What I claim as new is—

1. A furnace comprising a tiltable body provided with two chambers arranged in horizontal line, one of said chambers constituting a preheating-chamber, and the other an augmenting-chamber, a vertical partition between the two chambers having an eccentric opening 125 for establishing communication between the 130

two chambers for the passage of flame or gases when the furnace-body is in its melting position and for establishing communication between the chambers for the passage of molten metal from the preheating-chamber to the augmenting-chamber and for closing off said communication when the furnace-body is tilted for pouring.

2. A furnace comprising a cylindrical, tilt-able body provided with two chambers arranged in the longitudinal direction of the furnace and separated by a partition having an eccentric opening, a charging-opening leading to the one chamber, a pouring-opening 15 from the other chamber; said openings to the several chambers and the opening in the partition being so relatively disposed as to permit the discharge of molten metal from one chamber to the other, and the discharge of the 20 molten metal through the pouring-opening when the furnace is correspondingly tilted.

3. A furnace having two chambers mounted to rotate together and communicating with one another through a port, eccentric to the axis

of rotation, for establishing communication 25 for the passage of flames or gases from one chamber to the other when the material is being melted and for permitting the passage of the molten material from one to the other when the two chambers are rotated.

4. A furnace comprising a tiltable body provided with two chambers arranged in horizontal line, and a vertical partition between said chambers having an eccentric opening for establishing communication for the passage of 35 flames or gases from one chamber to the other when the body is in its melting position, and for establishing communication between the chambers for the passage of the molten metal from one to the other when the body is tilted. 40

In testimony whereof I have hereunto set my hand in the presence of two subscribing witnesses.

ARTHUR B. GRIFFEN.
